UNITED STATES PATENT OFFICE.

AUGUSTUS F. SHRIVER, OF NEWCASTLE, CALIFORNIA, ASSIGNOR TO HIMSELF AND FRED G. HATCH, OF SAME PLACE.

DESIGN FOR A SPOON.

SPECIFICATION forming part of Design No. 25,852, dated August 4, 1896.

Application filed July 1, 1896. Serial No. 597,777. Term of patent 14 years.

To all whom it may concern:

Be it known that I, AUGUSTUS F. SHRIVER, of Newcastle, in the county of Placer and State of California, have invented and produced a new and original Design for a Spoon, of which the following is a full, clear, and exact description.

Reference is to be had to the accompanying drawing, forming a part of this specification, in which the figure represents a perspective view of a spoon embodying my new design.

The leading feature of my design consists in the spoon having a straight handle and a bowl disposed in general at an angle to the axis of the handle and joining the handle by

a rearwardly-curved part *a*, the forward end of the bowl being rounded and in line with the handle.

Another feature of the design resides in the round handle having cross-sections of different diameters, the largest section being outermost.

I claim—

The design for a spoon herein shown and described.

AUGUSTUS F. SHRIVER.
